UNITED STATES PATENT OFFICE.

ADOLPH SCHMITT, OF BOGOTA, NEW JERSEY, ASSIGNOR TO ROYAL METAL LIGHTING FIXTURE CO., INC., A CORPORATION OF NEW YORK.

DESIGN FOR A BRACE FOR LIGHTING FIXTURES.

Application filed April 16, 1926. Serial No. 17,320. Term of patent 3½ years.

To all whom it may concern:

Be it known that I, ADOLPH SCHMITT, a citizen of the United States, and a resident of Bogota, county of Bergen, and State of New Jersey, have invented a new, original, and ornamental Design for a Brace for Lighting Fixtures, of which the following is a specification, reference being had to the accompanying drawing, forming a part hereof.

In the drawing:

Figure 1 is a side elevational view of the brace for lighting fixtures; and

Figure 2 is a diagrammatic side of the same.

I claim:

The ornamental design for a brace for lighting fixtures, as shown.

ADOLPH SCHMITT.
